CLAIM

The ornamental design for a child bowl as shown and described.

DESCRIPTION

FIG. 1 is a front view of a child bowl according to the present application;

FIG. 2 is a left side view of the child bowl;

FIG. 3 is a right-side view of the child bowl;

FIG. 4 is a top view of the child bowl;

FIG. 5 is a bottom view of the child bowl; and

FIG. 6 is an oblique view of the child bowl.

The broken lines of FIG. 5 represent portions of the structure that form no part of the claim.
